(57) **CLAIM**

The ornamental design for a display screen with graphical user interface, as shown and described.

DESCRIPTION

The FIGURE is a front view of a first image for a display screen with graphical user interface showing my new design.

The peripheral dash-dot-dash broken lines illustrate a display screen or portion thereof and form no part of the claimed design. The dashed broken lines within the peripheral dash-dot dash lines illustrate portions of the graphical user interface which form no part of the claimed design. The tonal shading indicates a contrast in appearance.
